UNITED STATES PATENT OFFICE.

GEORGE B. KEPLINGER, OF CHICAGO, ILLINOIS.

MOUNTING FOR PHOTOGRAPHS, MEDALLIONS, &c.

SPECIFICATION forming part of Letters Patent No. 782,199, dated February 7, 1905.

Application filed February 29, 1904. Serial No. 195,732.

To all whom it may concern:

Be it known that I, GEORGE B. KEPLINGER, a citizen of the United States, residing at Chicago, in the county of Cook and State of Illinois, have invented certain new and useful Improvements in Mountings for Photographs, Medallions, &c., of which the following is a specification.

This invention relates to a device for mounting medallions, photographs, art pictures, and the like, and has for its object to provide an attachment for the support by which the medallion or picture is carried and by means of which it may be attached to a frame, so as to give the same the appearance generally of an ordinary framed picture.

The invention comprises generally a supporting-back upon which the picture, medallion, or photograph is mounted and having prongs projecting therefrom and a frame or panel provided with apertures through which the prongs pass, the prongs being bent over to secure or fasten the back plate to the frame.

The invention consists of the combination and arrangement of parts hereinafter particularly described, and specifically designated in the claims and illustrated in the accompanying drawings, in which—

Figure 1 is a front elevation of a picture or the like mounted in accordance with my invention. Fig. 2 is a section, on an enlarged scale, on the line 2 2 of Fig. 1, showing the prongs turned over against the frame to secure the back plate. Fig. 3 is a rear elevation of a portion of the frame. Fig. 4 is a fragmentary view of the back plate, and Fig. 5 is a section on the line 5 5 of Fig. 3.

The photograph, picture, or other article to be mounted is provided with a back plate of rigid material, preferably consisting of a thin sheet of metal. In the present instance I have shown the invention applied to the mounting of art pictures covered by or impressed on sheets of celluloid and the like material. Such pictures, which are well known and are very popular owing to their inexpensiveness, usually consist of a sheet of celluloid or print 11, provided with a back plate 10 and secured thereto by an interposed plate 12, turned over the edge of the plate 10 to clamp the inturned

edge 13 of the sheet of celluloid against the back plate. The exact character of the back plate 10 and the means for securing the picture, photograph, or medallion thereto are, however, immaterial.

55

In carrying out my invention the back plate 10 is provided with a plurality of prongs 14, which are shown in the present instance as located at the corners of the back plate. Any suitable number of these prongs may be employed and located at any convenient points on the back, and these prongs may be provided in any suitable manner, as by stamping them up or cutting them from the material of the back, as shown in the drawings.

65

The frame 15, to which the back 10 is designed to be attached, may be of any suitable size and configuration and ornamented in any desired manner and may be made of any preferred material, as a sheet of metal; but preferably it consists of a wood panel. This panel is provided with openings or apertures 16, coinciding with the prongs 14 of the back 10. To secure the supporting-back carrying the picture, medallion, or photograph to the frame 75 or panel, the prongs 14 are passed through the apertures 16 and turned or bent over against the rear face of the frame, as illustrated in Figs. 2 and 5. To secure a more rigid attachment when a wood panel is employed, in order 80 to prevent the prongs working loose washers 17 may be threaded on the prongs to receive the bent ends of the latter, as shown in Fig. 5. When the medallion or other article is of the character hereinbefore described and provided 85 with the overturned edge 13, as shown in Fig. 2, such edge is clamped between the back plate 10 and the frame or panel 15, which thereby provides a clamp for more securely holding the celluloid sheet 11 in position.

90

The frame 15 is preferably provided on its back with a rib or beading 18, inclosing the protruding bent ends of the prongs 14, as shown in Figs. 2 and 5, and a covering 19, of paper or other suitable material, may be 95 pasted upon the rib or beading to conceal the attaching devices.

The invention herein described provides an inexpensive mounting or frame particularly adapted for use with pictures or photographs 100.

mounted on or used with a celluloid facing, which requires when used in this connection a rigid backing or plate to support the same. Moreover, when mounted in accordance with 5 my invention the pictures are provided with a frame imparting to them the appearance of a picture framed in the usual manner and adapted to be hung against the wall, &c.

Having described my invention, what I claim 10 as new, and desire to secure by Letters Patent, is—

1. The combination with a back plate having prongs projecting therefrom, a facing-sheet, a securing-plate having an inturned flange securing the edge of the sheet between 15 such flange and the back plate, and a panel having apertures through which the prongs pass, the said prongs being bent over against the panel to secure the back plate to the said panel.

2. The combination with a metal back plate 20 having prongs cut therefrom, a sheet of celluloid, a securing-plate having an inturned flange securing the edge of the celluloid between such flange and the back plate, a frame having apertures through which the prongs 25 pass, washers on the prongs, the latter being bent over against the washers to secure the back plate to the frame, a rib on the back of the frame and surrounding the ends of the prongs and a covering secured on the rib to 30 conceal the ends of the prongs.

In testimony whereof I affix my signature in presence of two witnesses.

GEORGE B. KEPLINGER.
